DISINFECTING DEVICE FOR WATER-CLOSETS AND THE LIKE.

Application filed April 8, 1927, Serial No. 181,951, and in Australia April 15, 1926.

Our invention relates to an improved disinfecting device for water closets and the like.

It is often desired to use disinfectant or deodorizers and the like in water closets, more especially when these are in an enclosed space such as the room of a house, and the object of the present invention is to provide a device which will automatically supply any desired quantity of disinfectant or the like to the closet whenever the pan is flushed.

The device consists of a container (which may be the vessel in which the disinfectant or the like is sold) such container being filled and sealed up with the exception of two small openings at one end which are preferably in proximity to each other.

One of these openings is through a lug or projection so arranged that when the device is standing in operating position in a cistern the outlet will be at a lower level than the other opening.

The object of this arrangement is to provide two distinct openings into the vessel at different levels so as to ensure discharge from the vessel whenever these holes are both uncovered. Each of these openings is adapted to be closed by a valve, each valve having attached to it a float which is sufficiently buoyant when under water to lift the valve and to hold it in a closed position against its opening on the under-side of the disinfecting container but each valve and float is heavy enough when not sustained by the water to drop away from the outlet or valve seating thus leaving a passage of more or less capacity as desired.

These valves are made of brass, gun metal or other non-rusting material and preferably consist of vertical rods having needle points and are so guided that they rise and fall in true vertical alignment with the valve seats.

We provide guides for the lower end of each valve beneath which there is an internally screw threaded opening for the accommodation of an adjusting screw upon the upper end of which the valve comes to rest. This arrangement enables the traverse of the valve to be adjusted by elevating or depressing the screw thereby regulating the admission of air and the discharge of disinfectant as will be readily understood.

The screws also enable the valves to be

tightly forced against their respective openings thus sealing the container when not in use for transport purposes.

If this vessel is stood in an inverted position in the cistern as illustrated it is obvious that every time the cistern discharges its water the floats will become inoperative and the valves will drop away from their seats. Owing to the difference of level of the two openings air will enter the vessel through the higher opening and disinfectant will be discharged through the lower opening, the amount of discharge depending upon two factors viz:—the time the valves are off their seats during the fall and subsequent rise of water in the cistern, and the amount of opening the valves are capable of presenting due to the setting of their respective adjustment screws.

In practice it is found that when some cisterns are emptied the inflowing water produces water waves in the cistern of sufficient size to make the floats respectively rise and fall. To overcome this difficulty we prefer to put a light metal shield around the floats so as to protect them against this action.

For the better elucidation of our invention we will now describe the same by aid of the accompanying illustrative drawings wherein:—

Fig. 1 is an elevation of the device illustrating a screw top jar or disinfectant container which may be modified in construction.

Fig. 2 is a section through line A—B showing the shield around the valve floats.

In both of the illustrations similar letters of reference are used to denote similar or corresponding parts wherever they occur.

In the drawings *a* is a vessel preferably made of glass and provided with a screw threaded neck *a'*. A screw threaded cover is shown at *b* and when the vessel is inverted this cover forms a floor to the upper chamber and is provided with a valve seat *c* for the air inlet and a valve seat *d* for the disinfectant outlet, the latter being at a lower level than the former.

We have illustrated a valve spindle *e* terminating in a needle point for the air inlet and a similar spindle *f* for the outlet of the disinfecting material. Both of the valves are mounted upon a float of any convenient kind, but which the simplicity of structure

may consist of a cork which may be varnished or otherwise rendered more impervious to moisture such floats being illustrated for the air and disinfectant respectively at *g* and *h*.

We also provide a guide plate *j* for the bottom of the valves, there being an extension *k* of the cover which supports the guide plate and constitutes a wave shield for the protection of the floats. This shield may completely surround the floats or it may be open as illustrated in Fig. 2 so that the valves may be easily examined and adjusted.

Upon the guide plate *j* we form the screw threaded recesses *l* and *m* respectively below the air and disinfectant valve. These may be an integral portion of the guide plate or support *j* and are adapted to accommodate the adjusting screws *n* and *o* by which the effective height of the valves in relation to their respective outlets may be easily adjusted. The opening in the shield is shown at *n* in Fig. 2 of the drawings.

We also provide a metal band *q* which fits round the container and has a flexible steady-ing hook *r* attached thereto. This band can be elevated or depressed to enable the hook to fit over the wall of the water cistern and may be varied in height according to requirements.

In practice it is found that the air inlet always requires a larger opening than the disinfectant outlet and it will of course be understood that the air inlet will be above the level of the water in the flushing cistern after the flush has been made, but the water

will gradually rise and close both valves automatically.

What we claim is:—

1. In a device for disinfecting water closets and the like, a sealed vessel adapted to stand in the cistern, said vessel having an air inlet opening and a discharge disinfecting opening at its lower end, the inner ends of which are approximately on the same level inside the vessel, the outer ends of the openings or tubes being at different levels, a valve for each opening, and floats for controlling the valves, said floats being located below the valves in the flushing cistern and operated by the fall and rise of the water in the cistern, each time the water is discharged and the cistern is refilled.

2. In a device for disinfecting water closets and the like as claimed in claim 1, means for elevating or depressing the valves for adjusting the inlet and outlet openings to regulate the rate of discharge of disinfectant from the vessel and the admission of air thereto, such device being also applicable for sealing up vessels when charged with disinfectant or the like during transit.

3. In a device for disinfecting water closets and the like as claimed in claim 1, the combination therewith of a wave shield to protect the floats for interference by wave influence.

In testimony whereof we affix our signatures.

LEWIS ERNEST SAUNDERS.
